UNITED STATES PATENT OFFICE.

LERoy S. DEAL, OF GLEN ELLYN, ILLINOIS.

PAPERHANGER'S PASTEBOARD.

Application filed March 15, 1926. Serial No. 94,873.

The object of my invention is to provide a foldable reinforced pasteboard divided into three sections, folding with its working surface inward; to provide for keeping the 5 paperhangers' straightedge inside of the folded pasteboard; and to provide for keeping in place, yet easily removable, on the pasteboard the zinc strip commonly used to cut the paper on.

10 In the drawings Fig. 1 is a top plan view of my pasteboard and straightedge, unfolded and ready for use, resting on suitable supports; Fig. 2 is an elevation showing my pasteboard completely folded and locked, 15 with the straightedge inside; Fig. 3 is a cross-section of my pasteboard, unfolded, in the plane indicated by line 3-3 in Fig. 1; Fig. 4 is a cross section of my pasteboard, completely folded, with the straightedge inside, in the plane indicated by line 4-4 in Fig. 2; Fig. 5 is an enlarged detail sectional elevation in the plane indicated by line 5-5 in Fig. 4; and Fig. 6 is a perspective view of one of the hinge-members used in my 25 device.

Referring to the drawings, my pasteboard 11, resting on supports 12, is made in three sections, 13, 14, and 15, of a width of approximately 7, 12, and 12 inches, respectively. These sections are held together by 30 hinges 16 uniting sections 13 and 14, and hinges 17, uniting sections 14 and 15.

Hinges 16 are single-joint hinges, but in order that sections 13 and 14 may be brought into close juxtaposition when my pasteboard is unfolded, ample recesses 18 for joints 19 and shank portions 20 are provided in the adjoining edges 21 and 22 of sections 13 and 14. Furthermore, in order that joints 19 may be automatically withdrawn below the level of the working surface 23 of pasteboard 11 whenever it is unfolded, I make shanks 24 of hinges 16 of spring metal, and make shank portions 20, carrying joints 19, 35 so short that when shanks 24 are in normal position, joints 19 lie below the level of surface 23. In order to make it nevertheless possible to fold section 13 upon section 14, I provide in their lower surfaces, for the distance of half an inch or so, adjoining recesses 18, slanting depressions 25 to make room for the springy ends 26 of shanks 24, adjoining portions 20, when section 13 is folded upon section 14, thereby necessitating bringing the axis of joints 19 to the level of working surface 23. It is evident that

with hinges 16 thus constructed and arranged, joints 19 will automatically be withdrawn below surface 23 by the straightening out of ends 26, snapping back out of 60 depressions 25, whenever my pasteboard is unfolded.

Hinges 17 are double jointed and arranged so as to bring sections 14 and 15 into close juxtaposition when they are unfolded, but to separate them to a distance equal to the thickness of my pasteboard, usually one-half inch, plus reinforcements, whenever section 15 is folded over upon section 14, or rather upon section 13 which 70 is first folded upon section 14. My preferred method for constructing each hinge 17 is as follows: Two metal strips, each about one inch wide and three inches long are each folded so as to form a member 27 75 with a substantial base 28, having two flanges 29 projecting therefrom at right angles and forming a slot 30. Members 27 are then placed end to end so that their slots 30 are in registry with each other, and 80 are hinged connected by a metal strip 31, oscillatably held in each slot 30 by a riveted pin 32 penetrating flanges 29 and strip 31. The openings for pins 32 in flanges 29 and strip 31 are so arranged that the distance between the centers of the openings in strip 31 is equal to twice the average distance from the centers of the openings in flanges 29 to the upper edges of flanges 29, plus the 85 thickness of my pasteboard. Strip 31 is made of sufficient width to substantially equal the depth of slots 30, and of a length, beyond the centers of the openings in it, equal to the distance from the center of these openings to the bottom of slots 30. 90 The ends of strips 31 are cut square at their upper corners 33 to conform to these dimensions, and therefore to act as stops when hinges 17 are folded, but are rounded at 95 their lower corners 34 to permit folding of hinges 17. This construction has the advantage that when section 15 is folded over upon sections 13 and 14, it is brought definitely into a position directly above section 14, in such manner that it is held there rigidly, with no chance for friction between it and the other sections. Hinges 17 are 100 preferably inserted into suitable slots 35, cut into members 14 and 15 to accommodate flanges 29, and into adjoining depressions 36, formed in the outer or lower faces of sections 14 and 15 to accommodate bases 28,

and are held in place by screws 37; members 27 being preferably so dimensioned that when they are in the position described, the upper edges of flanges 29 are flush with surface 23.

In surface 23 of one of the sections of my pasteboard, preferably narrow section 13, there is formed a shallow longitudinal depression 40. In this depression there is held, by any suitable means, a very shallow metallic trough 41, with open ends, the longitudinal upright edges 42 of which are bent over inwardly so as to form the trough into a slide adapted to firmly hold in place a metal strip of suitable width inserted into it from either end. Into this trough or slide 41 I insert the zinc strip 43 commonly used as a cutting base by paperhangers. The slide is so arranged that the upper surface 20 of its bent-over edges 42 is just flush with surface 23.

My sections 14 and 15 are preferably reinforced by corrugated metal strips 44 which are preferably superimposed on shanks 24 and bases 28, and are in part held in place by the same screws which hold shanks 24 and bases 28 in place.

My straightedge 45 is made of the same thickness as my pasteboard, and of such width, about three and a half inches, that it just fits snugly into the place, between section 13 and strips 31, left between sections 14 and 15 when my pasteboard is folded. In order to prevent it from sliding endwise, I provide in the adjoining edge of section 13 a projecting pin 46, fitting into corresponding hole 47 in one of the edges of straightedge 45, or vice versa.

To securely lock my pasteboard in folded position, I provide oscillatable hooks 48, fastened to the outer edge of sections 15, adapted and arranged to be placed in engagement with the shanks of screws 49, projecting from that edge of section 14 which adjoins section 13 when my pasteboard is unfolded. Openings 50 are provided in the corresponding edge of section 13 to receive the projecting ends of these screws when my pasteboard is unfolded.

The principal advantages of my pasteboard are as follows:

A. While foldable pasteboards have heretofore been used, none, as far as I am aware, has been made, prior to my invention, which made it practicable to fold the board with its working surface toward the inside. The hinges customarily used would either not permit such folding, or would project above the working surface. Yet folding the working surface inward means a great advantage. It prevents marring in transportation and otherwise, and keeps the working surface clean.

B. No one has heretofore provided, as

far as I know, a pasteboard which permitted a folding together of three sections. Yet in view of the fact that the customary pasteboard is about 31 inches wide, and only one-half inch thick, a treble fold makes a much better package than a mere double fold.

C. No one has heretofore provided for space inside of the folded pasteboard for the straightedge; yet it will readily be understood that it is important to preserve the straightedge from being dented or otherwise marred in transportation; furthermore that to transport it by itself is awkward, on account of its length. Hence the arrangement made by me for the straightedge is of considerable advantage.

D. The zinc strip, customarily used by paperhangers as a base for their rotary trimmer to cut on, has, as far as I am aware, heretofore always been either nailed on the pasteboard or been carried separately. When it was nailed on, the nailheads had a tendency to dull or otherwise damage the cutter; furthermore when the zinc strip had to be replaced, as is necessary from time to time, the nails holding it had to be pulled, leaving holes in the pasteboard, and causing other damage. When the strip was carried separately, it had a tendency to slide about and had to be rolled for transportation and unrolled for work. With my arrangement the zinc strip is always in place; no nailheads mar it, and it is easily replaceable without any damage whatever.

It is evident that the details of construction set forth by me might be changed or deviated from in numerous particulars without departing from the spirit and essence of my invention. All such changes I intend to cover by my claims.

I claim:

1. A paperhangers' pasteboard foldably divided into two wide and one narrow section, the narrow section being one of the outer sections and joined to the middle section so as to be foldable upon it, and the other wide section being joined to the middle section so as to be foldable upon the narrow section, the parts being dimensioned so as to permit a paperhangers' straightedge to be placed alongside the narrow section between the two wide sections, in combination with means to prevent said straightedge from sliding lengthwise when so placed.

2. In combination with a paperhangers' pasteboard, a metallic slide entered into the working surface of the pasteboard, adapted to hold replaceably in position by means of bent-over longitudinal edges, the zinc strip commonly used by paperhangers as a base for papercutting.
